PRESS FOR CUTTING OR PUNCHING SHEET MATERIAL.

1,228,834.

Specification of Letters Patent.

Patented June 5, 1917.

Application filed December 8, 1916. Serial No. 135,743.

To all whom it may concern:

Be it known that I, AUGUST R. SCHOENKY, a citizen of the United States, residing at Somerville, in the county of Middlesex and 5 State of Massachusetts, have invented certain new and useful Improvements in Presses for Cutting or Punching Sheet Material, of which the following is a specification, reference being had therein to the 10 accompanying drawing.

This invention relates to presses for cutting or punching sheet material, and is shown applied to a design of machine adapted more particularly to the purpose of 15 dieing-out leather to constitute the upper parts of boots and shoes, although various features hereof could be used for dieing-out or cutting or punching other sheet material.

A typical example of a machine of the 20 class referred to, and which is the basis upon which the present invention constitutes an improvement, is that of the North British Patent No. 16,488 of 1904. My present machine, in common with the North cutting-out press, embodies a solid, heavy frame provided with a flat, horizontal bed, over which may be spread the sheet of material or leather to be cut, and a presser or 25 head of construction and weight adapting it to press a suitable die through the material resting on the bed. The die is usually a loose or detached member with knife edges at its lower side, and it may be placed in selected positions on the leather, according 30 to the nature or grain of the leather, to secure the best results. This presser is fitted on the machine so that it may be swingingly shifted over the bed to and from any desired cutting position. It is also fitted to 35 descend toward and recede from the bed. The machine is power-actuated, having a constantly rotating pulley or other power member and connections therefrom, including a clutch, by which the presser may be 40 moved toward and from the bed after it has been shifted into cutting position. Owing to variations in the height of the 45 dies which may be used and the wear which takes place on the bed or cutting block, 50 means is provided for predetermining the point of nearest approach of the presser to the bed, so that, when actuated, it will certainly drive the die through the leather without injuring the bed. This is performed by a vertical adjustment of the bed. 55

A controller or lever, located below the bed, is employed, having connections for bringing about the actuation of the presser, and, when the actuation ceases, automatic means comes into play for causing the presser to 60 come to rest in its elevated position, so that it may be swung free of the die and the die replaced in any desired position for a subsequent cut. The presser swings over the bed relatively to a carrier or pillar or slide 65 or ram, which is reciprocated vertically by an eccentric. The North machine, however, although having such structural features, is objectionable in certain respects, including 70 lack of sufficient rigidity of the various movable parts and lack of proper coördination between the bed and the presser and reduced efficiency resulting therefrom, and certain inconveniences in operation.

The principal object of the present improvement is to overcome the objections heretofore noted, and other objects and advantages of the present invention will be elucidated in the hereinafter following description of one form of embodiment in 80 which my invention may be carried out.

A design of machine has heretofore been proposed which has partly overcome the noted objections to the North machine, as shown in my prior Patent 1,068,455, but 85 only at the sacrifice of certain advantages pertaining to the North machine; and it is an object hereof to overcome all the objections while retaining all the advantages of the North machine. 90

To the attainment of the above referred to objects and advantages, the present invention consists in the novel cutting or punching machine and the novel features of design, combination and detail, herein 95 illustrated or described.

The principal features of the present invention which overcome the stated objections to the North machine are the following: All movable, adjustable or wearable 100 connections between the eccentric rod and the ram or pillar which it reciprocates are obviated, so that, at this point where the greatest strain occurs, the mechanism is absolutely durable and reliable in action. The 105 eccentric connection engages directly with the pillar, or with a part thereof practically integral and unitary with the body of the pillar, and permanent, non-adjustable and immovable. The adoption of this structure 110

is permitted by the illustrated novel combination of elements, wherein not only is the pillar non-rotating, the presser itself swinging with respect to the pillar, but the pillar 5 is also free from vertical adjustment, such as that of North, the bed itself in my machine being adjustable for the purpose of determining its correct relation to the presser. This stated coöperation is supplemented by the combination with the pillar 10 and the other elements mentioned of a presser of special structure, which, although rotatably arranged on the pillar, is constructed and connected so as to preclude any play or wear or distortion. This novel presser consists of several portions, a rotary bearing surrounding the pillar above the guide which guides the pillar, a presser head projecting forwardly from the bearing, 15 and a preferably rearward extension serving to extend to a second bearing located on the pillar below the guide, all these portions constituting a unitary rigid presser member having the movements which will be 20 more fully described. In these advantageous ways I secure sufficient rigidity of the various movable parts, and I thus avoid any reduced efficiency from lack of exact co-ordination between the bed and presser, even 25 though the speed of the machine be greatly increased, so that I am enabled to employ a well-known type of press clutch which takes effect quickly, and is herein shown operable by foot or hand, as convenient.

30 35 In the accompanying drawings disclosing one form in which my invention may be embodied, Figure 1 is a righthand elevation of the machine.

Fig. 2 is a front elevation of the same.

40 Fig. 3 is a front view of certain parts shown partly in section on the line 3—3 of Fig. 1.

Fig. 4 is a similar view on the line 4—4 of Fig. 1.

45 Fig. 5 is a section taken on the plane 5—5 of Fig. 1.

Fig. 6 is a section taken on the plane 6—6 of Fig. 4.

Above a four-legged base 10 is firmly secured 50 the main frame 11, which constitutes a support for the movable elements of the apparatus. Above the forward part of the frame is the bed or cutting block 12, which may be constructed in the usual manner of 55 pieces of wood held together and secured by clamping devices 13 at the top of a support 14, vertically adjustable in the frame in a manner and for purposes to be later described.

60 Located at a higher level than the bed is the shifting or swinging presser or head 15, provided for convenience with a handle 16 at its forward end, by which it may be 65 swung horizontally into any desired position over the bed, according to the location

of the die, or may be swung to the right or left from above the bed, to give the operator ample room for inspection of the stock or leather and placing the die thereon to the best advantage.

The leather or other sheet material 16 is supposed to be spread flatwise over the bed, and a loose die 17 is laid on the leather with its cutting edge downward, so that, when struck by the descending presser, the die 75 will be pressed through the material, thus cutting out the desired shape.

80 Referring to the presser member 15, this, as shown in Fig. 2, has sufficient width so that it need be swung merely into approximate position and will more than cover the die or dies to be operated.

85 In order to give the presser this horizontal swinging movement and an up-and-down reciprocation, I have provided a slide or ram 18, which, being usually upright, may be termed a pillar, and which is made hollow for lightness, and adapted to carry the presser and to give it its up-and-down movements, while the presser is connected 90 to the carrier or ram by rotary means, so as to permit the presser swinging movements, thus dispensing with any complication due to the ram having to rotate in addition to its reciprocation. As will be noticed from Fig. 1, there are a number of bearings along the length of the ram 18. The topmost bearing 19 is a rotary bearing and consists of a cylindrical portion rigid with the presser engaging around the ram. From this bearing extends downwardly a rigid extension 20, at the foot of which and spaced below the bearing 19 is a second rotary bearing 21 between the presser and ram. The parts 15, 19, 20 and 21 are shown as a 100 single casting constituting the presser, and, by reason of the bearings 19 and 21, it is capable of bodily rotating or swinging relatively to the ram 18. The presser is compelled to move vertically with the ram by 105 being confined between a shoulder 22, provided at the upper end of the ram, and a thrust bearing 23 of the rolling ball type, between the cylindrical bearing 19 and a collar 24 below it rigidly secured upon the ram. The collar 24 is shown as detachable for the purposes of assemblage, and as adjustable for taking up lost motion, by means of screw threads formed at 25, and a clamping device or bolt 26 serves to lock the collar in proper adjustment.

110 It being understood that the ram 18 is vertically reciprocable, but is incapable of rotation, it will be seen that the construction recited permits the free swinging of the 125 presser into and out of cutting position while compelling it to partake of the vertical ram movements.

The ram 18, which is preferably cylindrical, constitutes in effect a slide for the pur- 130

pose of its up-and-down motion, and to suitably support and guide it in this motion it is provided with two slideways or supporting bearings 27 and 28, which constitute extensions of the frame 11.

5 The bearing 27 is located between the frame bearings 19 and 21, before referred to, and the bearing 28 is located beneath the bearing 21, so that the two rotary bearings 10 and the two slide bearings are alternated in position, giving great strength and freedom from play or lost motion. This arrangement, furthermore, dispenses with the objectionable overhanging structure illustrated in my said Patent No. 1,068,455, which merely increases the height and weight of the machine and obstructs the light required by the operator for the best performance of his duties.

20 The swinging of the presser is most advantageously performed by hand, but its vertical reciprocation requires power. Either the upward or the downward stroke should be a power stroke, and I prefer that both 25 the upward and downward strokes are by power. As a convenient source of power I show a belt pulley 30, which is loosely mounted on the main shaft 31 of the machine, the shaft being adapted by a clutch 30 to be described to be driven or stopped, as required. Upon the shaft 31 is eccentric 32 for reciprocating the ram 18 and the presser, and it may be such as to give a fixed extent of motion something under an inch in throw.

35 It will be noted that the shafting which receives and transmits the power through the eccentric to reciprocate the presser is arranged similarly to that of the Hodges, Ash- 40 ley and Grosvenor British Patent No. 3276 of 1879, so as to extend forwardly and rearwardly at the lower central part of the frame, which is a convenient arrangement permitting the eccentric to be placed near the front end of the shaft beneath the ram, 45 pillar or plunger, and the power pulley so far to the rear that the power belt, however arranged, will not stand in the way of the presser as it is swung toward the side of the machine.

50 My heretofore described arrangement of bearings for the ram 18 permits a very effective and durable connection to the eccentric, as best shown in Fig. 5, and one which is devoid of adjustment and practically incapable of wear, this being rendered possible 55 by the fact that the relative adjustment between the presser and bed is effected by vertically shifting the bed, as will be described.

Within the hollow lower end of the ram is 60 snugly and permanently secured by a pin 33 a strong steel plug 34, and between the lower end of the plug 34 and the eccentric 32 ex- 65 tends the strap or connecting rod 35, which is short in length and is snugly fitted, to avoid lost motion or wear, at both its upper

and lower ends. Each rotation of the shaft 31 throws the ram and presser downwardly and upwardly.

The shaft 31, as seen in Figs. 1 and 6, is journaled in two spaced-apart bearings 36, 70 36, one forward and the other rearward of the eccentric 32, and each of the bearings 36 is provided with a removable bearing sleeve or bushing 37 to permit the insertion and removal of the shaft.

75 In order that the power of the constantly rotating power pulley 30 may be communicated at the proper times to the shaft 31 for actuating the presser, any suitable coupling device or clutch may be employed. Instead of employing a friction clutch such as that of North, which is thrown in engagement by the pressure of the control lever or pedal and gives a gradual easy starting, I prefer to employ a different, but well-known, type 80 of clutch, which may be engaged by a light tripping motion, as has been frequently employed in various cutting and punching presses.

85 In the drawings hereof I illustrate such a clutch, which for convenience is located on the same shaft 31 which carries the power pulley and eccentric.

The constantly rotating clutch member 90 consists of the power pulley 30, which at its forward side is constructed with a series of four shoulders or notches 39 formed by pieces of hardened steel to minimize wear.

The complementary clutch part turns and stops with the shaft 31, and comprises a 100 collar 40, keyed to the shaft and carrying the clutch parts for engaging the shoulders 39.

105 Instead of attempting to apply friction or other stopping means when the power is disengaged, I prefer to maintain a constant braking friction upon the collar 40, and an arrangement for this purpose is shown in the form of a felt strip 41, located between the collar 40 and a clamp ring 42, which latter may be tightened to the proper degree by a screw device 43, which passes through the extremities of the clamp ring and through a fixed lug 44 extending rearwardly from the frame of the machine. 110 This braking arrangement is such that, when the clutch is disengaged, the shaft is brought almost instantaneously and quietly to rest with the presser in its elevated position.

115 The clutch dog 46 is pivotally arranged 120 in a recess in the collar 40 in such a way as to permit it to engage with any one of the four shoulders 39, and, as seen in Fig. 4, a spring-pressed device 47 tends to force the dog 46 outwardly into the path of the 125 notches 39 on the rotating power pulley, so that the pulley may drive the collar and shaft, excepting when the dog is pressed into inoperative position by the means which will now be described.

Extending forwardly from the dog 46 is a pin 48, adapted to be engaged by a cam or shoe 49 before the shaft comes to rest. The operation of the shoe 49, as seen in Fig. 4, is to wedge the dog within the periphery of the collar, so as to cause it to disengage from the notches 39, which have up to that time been causing the rotation of the dog and shaft.

- 10 The shoe 49 is adapted to be shifted from and into operative position, and for this purpose is secured at the lower end of a swinging arm 50, fulcrumed at 51 to a rearwardly extending bracket 52. The arm 50 is made in two parts capable of adjustment for altering the position of the cam shoe, and, when adjusted, may be secured by the device 53, as seen in Fig. 4.

20 The shoe may be swung forwardly to remove it from operative position by swinging rearwardly an upward extension 54 of the arm 50, (see Fig. 1), against the opposition of a spring 55. The operative or rearward position of the shoe may be set or predetermined by the adjustable stop device 56, Fig. 1.

In Figs. 1 and 4 the parts are shown in their position when the machine is not running. The shoe 49 is in its rearward position, and it has forced the dog 46 radially inward, so that the shaft has been disengaged from the pulley and stopped by the friction band.

35 In order to start the machine it is only necessary to shift forwardly the cam shoe 49, so as to move it out of the path of the dog 46, permitting the latter to swing out of the recess in the collar, so as to engage in one of the notches 39 of the pulley, and there-
40 fore be rotated. This may conveniently be effected by a connecting rod 58, extending from the cam 50 forwardly, as seen in Fig. 1, its forward end being shown pivoted to an upwardly extending arm 59, secured at 45 its lower end to a rock shaft 60, having a pair of forwardly extending arms 61, shown as connected by a cross rod 62, which may serve as a pedal that can be conveniently depressed for closing the clutch and causing
50 the actuation of the presser.

As it may be sometimes desirable that the controller or clutch lever be accessible to the operator's hand, rather than the foot or some other part of his body, I have shown 55 a simple arrangement whereby the treadle device or foot controller described may be depressed by hand. A pair of opposite and upward connecting rods 63 extend to a hand controller or bar 64, which is conveniently
60 guided upwardly and downwardly by carrying levers 65. Hand control for tripping a clutch to apply power to a cutting or punching press was, however, known prior to the North patent, and I make no claim thereto.
65 The patents of Bigelow 113,618, Partington

458,480, Morgan 513,812 and Wetmore 729,822 and others show this plan.

It will be noticed that both the hand controller 64 and the foot controller 62 are below the presser, and, in fact, both are below 70 the cutting bed of the machine, as in the North patent. The hand controller 64 is, in fact, so far removed from the presser swinging handle 16 that the two would naturally be operated by different hands thus enhancing safety. 75

If it should be desired to control the machine solely by the hand controller, the foot controller could be adjusted rearwardly so as to be out of the way of the operator's feet, 80 and for this purpose the rock shaft 60 is fulcrumed upon a pair of adjustable lugs 66 at the right and left hand sides of the machine, which lugs may be slid rearwardly on the fixed frame bars 67. 85

As before stated, I have provided no means for adjusting the relation between the presser and its actuating eccentric, and the presser always moves upwardly and downwardly over a given path of movement. 90 Sometimes, however, relative adjustment with respect to the bed is required, for the reasons before explained, and for this purpose I have rendered the bed vertically adjustable in an efficient and convenient manner and without sacrificing its rigidity and efficiency as a cutting block. Extending downwardly from the support 14, above which the cutting block is supported, is a shank or plunger 69, which for convenience 100 may be cylindrical, and this plunger fits snugly within a cylindrical recess formed at 70 in the frame of the machine. To prevent rotation a keyway is cut in the plunger at 71, as seen in Fig. 2, engaged by a pin or 105 bolt 72.

The circularly recessed frame part is shown in Fig. 2 as being slotted from the top thereof for a considerable distance downwardly, and is formed with a pair of 110 opposite lugs 73 near the top, which lugs are bored for the reception of a locking bolt 74, which passes through the righthand lug and engages screw threads in the lefthand lug. This permits the frame to be tightly compressed about the plunger after the latter has been adjusted to the proper altitude. 115

The adjustment of the plunger 69 and the cutting block may, for convenience, be effected by a screw threaded device, as seen 120 in Fig. 1. This comprises a threaded shank 75, having a hand-wheel 76 at its lower exterior end and a shoulder at 77, which rests upon an apertured plate 78, confined within the lower end of the hollow frame part. The 125 threaded part of the shank 75 engages in an interiorly threaded member 79, integral with or secured within the plunger 69.

By this arrangement the turning of the hand wheel in one direction or the other 130

lifts and lowers the cutting bed to the desired point. Gravity causes its descent when lowered, and when finally adjusted the locking device 73, 74 finally secures the parts 5 in place.

The complete operation of the described apparatus may be as follows: The operator will spread the leather, skin, or other sheet material over the cutting block or bed 12, 10 and will lay the cutting die 17 in suitable position on the leather, as dictated by the condition of the material. Assuming that the hand-wheel 76 and the bed locking devices have been employed to properly adjust 15 just the height of the bed with respect to the presser, the operator may with the left hand swing the presser into cutting position over the die, and thereupon depress the hand controller 64 or the foot controller 20 62. This swings the cam shoe 49 forwardly from the dog 46, allowing the latter to become operative, so that the power pulley engages and drives the shaft 31, causing the descent, and then the lifting, of the ram 18 25 and the presser 15. If the operator has not released the pedal, the reciprocation will continue, but if he has released the pedal, the pin 47 on the rotating dog will meet and be forced inwardly by the cam shoe, thus disengaging 30 the clutch and permitting the shaft to be stopped by the friction band device, in a position with the presser elevated to substantially its maximum height above the bed. This permits the presser to be swung 35 to one side and the die repositioned for another cutting.

It will be noticed that, if the controller, hand or foot, be depressed and immediately released, power will be transmitted from the 40 driving member or pulley through the clutch, shaft, eccentric and ram to cause a single reciprocation or descent and rise of the presser, whereas, if desired, the controller may be held depressed, so as to cause 45 continuous or repeated reciprocations until the release of the controller.

I do not make any broad claim herein to the employment in a press of a tripping clutch, controlled by hand or foot lever, 50 which, like that shown in the present drawings, comprises a spring-pressed dog on the main shaft of the press, adapted to be engaged and driven by shoulders or notches on the driving member or pulley until released 55 by the throwing in of the dog through an axially shiftable throw-out device, nor to the application of friction to stop the shaft when so disengaged; since the expired Wheeler Patent No. 470,797 of 1892, shows a

60 power press having such a clutch-and-stop mechanism. My specific clutch differs *per se* in mere detail from that of Wheeler.

It will thus be seen that I have described a press for cutting-out and punching sheet material, attaining the objects and advantages

and embodying the principles of the present invention. Since many matters of design, arrangement, combination and other features may be variously modified without departing from the principles of the present 70 improvement, I do not wish to be limited to such features excepting in so far as specified in the appended claims.

What is claimed is:

1. A power press for cutting-out or punching leather or other sheet material, including, in combination with the machine frame, and the bed carried thereby; a non-rotating upright pillar reciprocable downwardly and upwardly; a laterally swingable presser 75 rotatably engaged upon and carried by the pillar and adapted to extend over said bed, said presser comprising a forwardly extending head, a rotary bearing at the rear of the head engaging the pillar, an extension 80 for a second rotary bearing, and a second rotary bearing also engaging the pillar, said second rotary bearing being provided on said extension and spaced vertically substantially from the first bearing, and said head and 85 extension and rotary bearings constituting a solid unitary member capable of bodily rotation relatively to the pillar and of reciprocation with the pillar; a guide on said frame engaging said pillar between said two 90 rotary bearings; and power connections for reciprocating the pillar at suitable times.

2. A power press for cutting-out or punching leather or other sheet material, including, in combination with the machine frame, and the bed carried thereby; a non-rotating upright pillar reciprocable downwardly and upwardly; a laterally swingable presser rotatably engaged upon and carried by the pillar and adapted to extend over said bed, 100 said presser comprising a forwardly extending head, a rotary bearing at the rear of the head engaging the pillar, an extension for a second rotary bearing, and a second 105 rotary bearing also engaging the pillar, said second rotary bearing being provided on said extension and spaced vertically substantially from the first bearing, and said head and extension and rotary bearings constituting a solid unitary member capable of 110 bodily rotation relatively to the pillar and of reciprocation with the pillar; a guide on said frame engaging said pillar between said two rotary bearings; power connections engaging the pillar at a point spaced below 115 the lower rotary bearing; and a second guide on said frame engaging said pillar between the lower rotary bearing and the power connections.

3. A power press for cutting-out or punching leather or other sheet material, including, in combination with the machine frame, and the bed carried thereby; a non-rotating upright pillar reciprocable downwardly and upwardly; a laterally swingable presser 125 ro-

tatably engaged upon and carried by the pillar and adapted to extend over said bed, said presser comprising a forwardly extending head, an upper rotary bearing at the rear of and substantially on a level with the head, a downward extension from said rotary bearing, a lower rotary bearing on said extension, said two rotary bearings engaging the pillar at spaced apart points, and 5 10 15 said head and extension and rotary bearings constituting a solid unitary member capable of bodily rotation relatively to the pillar and of reciprocation with the pillar; and a guide bearing on said frame engaging said pillar between said two rotary bearings.

4. A power press for cutting-out or punching leather or other sheet material, including, in combination with the machine frame, and the bed carried thereby; a non-rotating 20 upright pillar reciprocable downwardly and upwardly; a laterally swingable presser rotatably engaged upon and carried by the pillar and adapted to extend over said bed, said presser comprising a forwardly extending head, an upper rotary bearing at the rear of and substantially on a level with the head, a downward extension from said rotary bearing, a lower rotary bearing on said extension, said two rotary bearings engaging the pillar at spaced apart points, and 25 30 35 said head and extension and rotary bearings constituting a solid unitary member capable of bodily rotation relatively to the pillar and of reciprocation with the pillar; a guide bearing on said frame engaging said pillar between said two rotary bearings, a second guide bearing below the lower rotary bearing; and power connections engaging the pillar below all said bearings for 40 reciprocating it at suitable times.

5. A power press for cutting-out or punching leather or other sheet material, including, in combination with the machine frame, and the bed at the upper front thereof, an

upright presser-carrying pillar near the rear 45 of the machine; a rearward extension on the frame at substantially the level of the bed and giving support to the pillar; a laterally swingable presser rotatably engaged upon and carried by the pillar, said presser 50 comprising the following substantially unitary and rigidly associated parts, namely, an upper rotary bearing surrounding the pillar above said frame extension, a head extending forwardly from said upper bearing, a balancing arm extending rearwardly from said upper bearing, said rearward arm formed with a downward extension, and a lower rotary bearing on said extension surrounding the pillar below said frame extension; and power connections for causing relative up-and-down movements between the bed and presser.

6. A power press for cutting-out or punching leather or other sheet material, including, in combination with the machine frame, and the bed carried thereby; a non-rotating upright pillar; a laterally swingable presser rotatably engaged upon the pillar and adapted to extend over said bed, said presser comprising a forwardly extending head, a rotary bearing at the rear of the head engaging the pillar, an extension for a second rotary bearing, and a second rotary bearing also engaging the pillar, said second 70 75 rotary bearing being provided on said extension and spaced vertically substantially from the first bearing, and said head and extension and rotary bearings constituting a solid unitary member capable of bodily 80 rotation relatively to the pillar; an extension on said frame giving support to said pillar between said two rotary bearings; and power connections for reciprocating the presser at suitable times.

In testimony whereof, I have affixed my signature.

AUGUST R. SCHOENKY.
